UNITED STATES PATENT OFFICE.

WILLIAM F. DESTER, OF NEWARK, NEW JERSEY, ASSIGNOR TO U. S. TOOL CO., INC., OF EAST ORANGE, NEW JERSEY, A CORPORATION OF NEW JERSEY.

SAFETY IGNITER FOR GAS STOVES.

Application filed November 10, 1925. Serial No. 68,072.

This invention relates to gas burner igniting devices, more particularly as applied to multiple burners in stoves and has as one of its objects to provide an igniter that automatically lights the gas at any one or more burners that may be in open connection with the gas supply.

A further feature is in the provision of means which will immediately relight the burners should the flame, for any cause, become extinguished, thus avoiding the danger of escaping gas.

Another aim is to produce an igniter having a pilot flame so arranged as to be protected from drafts and which is practically unextinguishable so long as a supply of gas is maintained.

A still further object is to produce an igniter in the form of an attachment readily applicable to gas stoves of a modern type of construction without material change therein, the igniter being inexpensive to manufacture, easy to install and substantially indestructible in use.

These and other similar objects are accomplished by the novel design, construction and combination of parts hereinafter described and shown in the appended drawing, constituting a material part of this disclosure, and in which:—

Figure 1 is a top plan view of a conventional type of gas stove showing an embodiment of the invention as applied to the several burners.

Figure 2 is an enlarged perspective view of the pilot, its connections and housing, parts being broken away to show the construction.

Figure 3 is a fragmentary partial sectional partial perspective view of the same.

Figure 4 is a fragmentary side view of the pilot valve and control.

Around the top of the stove, as shown in the drawing, is a frame 5 having an inner lower seat rim 6 to receive and support open grid covers 7, below which are burners generally designated by the numeral 8.

These burners are of the multi-lobed type, each lobe having a plurality of fine perforations for the passage of gas jets to be ignited.

Each burner is connected by bent pipes 9 to atmospheric air inlets 10 having control shutters 11 and into which pass gas inlet tubes 12 controlled by cocks 13 and furnished

from a gas supply header 14, held to the frame of the stove by supports 15, all of these elements being old and well known.

So too is the pilot light connection tube 16 in communication with the header 14, 60 the tube being provided with a needle valve control 17, the screw 18 of which is held frictionally in adjustment by its encircling tension spring 19.

The inner portion of the tube 16 is curved 65 into an upright position after passing through a support 20, attached to the bottom wall of a cylindrical pilot housing 21, into which the screw-threaded end 22 of the tube 16 enters.

The bottom of the housing is provided with a plurality of perforations 23 for the inlet of air to the pilot burner 24, having a fine central tip 25, the burner being fixed on the end 22 of the supply tube and the 75 tube itself is held rigidly to the housing by clamp nuts 26 and 27, respectively inner and outer.

The cylindrical wall of the housing contains notches 28 in its upper edge and in 80 register therebelow are small screw-threaded openings 29 to receive screws 30 passing thru slotted openings 31 in curved pads 32 formed on offset brackets 33 spaced from the wall of the housing and having openings 85 34 registering with the housing notches 28.

The upper portions of the brackets 33 are bent at right angles outwardly, as at 35, attenuated in width and offset downwardly at 36, the material being formed into bands 37 90 terminating in pairs of lugs 38 provided with clamp screws 39.

Engaged adjustably in these bands are tubes 40, their outer ends being downturned and shaped to produce open bottomed receiving and dispensing funnel heads 41, disposed adjacently over the outermost perforation in the nearest lobe of each burner 8, as best seen in Figure 1.

The inner ends of the tubes 40 are formed 100 with a series of closely spaced annular grooves 42, having sharply defined corners and adapted to become severed upon being struck a blow, as with a hammer, or upon bending, the object being to shorten the tube 105 to a suitable length to extend from the burner perforation to a point adjacent and above the pilot tip 25.

The inner ends of the tubes 40 pass through the bracket openings 34 and notches 110

28 of the housing to extend radially from the pilot, these inner ends being covered by a cap 43 having a downturned flange 44 spaced from the housing 21, to permit the 5 passage of air, the cap flange having recesses 45 to engage over the tubes 40, resting upon them to clear the upper edge of the housing, as best seen in Fig. 3.

In operation it is to be understood that the 10 valve 17 is adjusted to permit a steady but fine flow of gas from the header 14 to the pilot jet 25, which is intended to be maintained in a constantly ignited condition.

Upon opening any of the cocks 13, gas 15 will pass from the header to the selected burner and, escaping through the perforated lobes, will find its way, in part, into the funnel head 41 to be conducted through the tube 40 to the pilot flame, whereupon an 20 instant slight explosion takes place and flame is caused to return through the tube 40 to the head 41, igniting the several jets of gas escaping from the perforations in the burner instantly and without action on part 25 of the operator, who has merely to open the cock or cocks of the burners it is desired to use.

This automatic igniting action will take 30 place obviously if the cocks are inadvertently opened and also if the gas at the burners be accidentally extinguished by a draft, the wind, water from boiling vessels or other causes, thus affording assurance against the loss of gas and consequent 35 danger.

It will be seen that several burners may be controlled by a single igniter, that the pilot light is so arranged as to avoid being blown out under ordinary circumstances and 40 that the design of the same is neat and unobtrusive.

The foregoing disclosure is to be regarded 45 as descriptive and illustrative only, and not as restrictive or limitative of the invention, of which obviously an embodiment may be

constructed including many modifications without departure from the general scope herein indicated and denoted in the appended claims.

Having thus described my invention, what 50 I claim as new and desire to secure by Letters Patent, is:—

1. The combination with a gas burner, a pilot tip and a gas supply source, of a pipe connecting said supply source with said tip, 55 a control valve in said pipe, a housing completely enclosing said tip, a cap loosely engageable over said housing having an intervening air space, a bracket adjustably engaged on said housing, a tube adjustable in 60 said bracket to extend horizontally through the wall of said housing into the path of flame from said tip, said tube having a series of weakening grooves whereby shortening is facilitated, and means on the outer 65 end of said tube adapted to collect gas from said burner and deliver to said tip.

2. The combination with a gas stove having a plurality of burners, a pilot burner interjacent, and a gas header in controllable 70 communication with each of said burners, of a housing enveloping said pilot burner, said housing having a perforate bottom, a pipe leading from said header through the bottom wall of the housing, means for adjustably engaging said tube therein, said pipe bearing the pilot burner, brackets laterally adjustable on said housing, said brackets having radially extending loops, tubes adjustable in said bracket loops, said 75 tubes entering the housing and terminating adjacently above the pilot burner, a cap on said housing resting on said tubes, said cap being spaced from the housing, and funnels on the outer ends of said tubes disposed directly over the adjacent openings in said burners.

This specification signed and witnessed this thirty first day of October, 1925.

WILLIAM F. DESTER.
